UNITED STATES PATENT OFFICE

159,572

TELEVISION CABINET

Samuel E. Adler, Chicago, Ill.

Application January 21, 1949, Serial No. 376.

Term of patent 14 years

(Cl. D56—4)

To all whom it may concern:

Be it known that I, Samuel E. Adler, a citizen of the United States and resident of Chicago, in the county of Cook, State of Illinois, have invented a new, original, and ornamental Design for a Television Cabinet, of which the following is a specification, reference being had to the accompanying drawing, forming a part thereof.

The figure is a perspective view of a television cabinet showing my new design.

The back of the cabinet is plain, and the opposite side is similar to the side shown.

The dominant features of my design reside in that portion shown in full lines in the drawing.

I claim:

The ornamental design for a television cabinet, as shown and described.

SAMUEL E. ADLER.
